UNITED STATES PATENT OFFICE

113,518

DESIGN FOR A SHAVING DEVICE

Frederick Meyer, Union, N. J., assignor to Art Metal Works, Inc., a corporation of New Jersey

Application March 9, 1938, Serial No. 75,699

Term of patent 7 years

To all whom it may concern:

Be it known that I, Frederick Meyer, a citizen of the United States and a resident of Union, in the county of Union and State of New Jersey, have invented a new, original, and ornamental Design for Shaving Device, of which the following is a specification, reference being had to the accompanying drawing forming part thereof, wherein Figs. 1 and 2 are side and edge elevational views, respectively, of the device, and Fig. 3 is a top plan view thereof.

The perforations as shown in Fig. 3 are intended to continue substantially throughout the entire circular area of said figure.

The distinctive features of the design reside in the portions indicated in solid lines.

I claim:

The ornamental design for a shaving device, substantially as shown and described.

FREDERICK MEYER.
